(57) **CLAIM**

The ornamental design for a bolster dressing, as shown and described.

DESCRIPTION

FIG. 1 is a perspective view of the present invention of a bolster dressing;

FIG. 2 is a top view of the bolster dressing of FIG. 1;

FIG. 3 is a front side view of the bolster dressing of FIG. 1;

FIG. 4 is a back side view of the bolster dressing of FIG. 1, being the opposite view of FIG. 3;

FIG. 5 is an end side view of the bolster dressing of FIG. 1, with the opposite end side view being a mirror image thereof; and,

FIG. 6 is a bottom view of the bolster dressing of FIG. 1.
